UNITED STATES PATENT OFFICE.

ALVA L. KITSELMAN, OF RIDGEVILLE, INDIANA.

DESIGN FOR A PATTERN FOR WIRE FENCING.

SPECIFICATION forming part of Design No. 27,435, dated July 27, 1897.

Application filed June 16, 1897. Serial No. 641,070. Term of patent 7 years.

To all whom it may concern:

Be it known that I, ALVA L. KITSELMAN, a citizen of the United States, residing at Ridgeville, in the county of Randolph and State of Indiana, have invented a new and original Design for a Wire-Fence Pattern, of which the following is a specification.

This invention relates to a new and original design for a wire-fence pattern; and it has for its object to provide a design of this character that shall be both useful and ornamental.

The leading feature of the design resides in a wire-fence pattern having a pair of opposite parallel twisted selvage cables provided at intervals with pointed projections or barbs, a series of straight parallel warp-wires arranged in the space between and parallel with the selvage cables, and interwoven weft-wires having twisted portions encircling the warp-wires and cables at their points of intersection therewith, said weft-wires forming the boundary-lines of longitudinally and transversely aligned rows of diamond-shaped figures, the diamond-shaped figures in each longitudinal row thereof being bisected by one of the straight warp-wires.

In the drawing the figure is a plan view or elevation of a section of fence-pattern embodying the herein-described design.

Referring to the drawing, the numerals 11 30 designate the opposite parallel twisted selvage cables of the pattern, which cables are provided at intervals with pointed projections or barbs 2. In the space between the opposite parallel cables 1 are arranged straight 35 parallel warp-wires 3, which are disposed in planes parallel with the said cables 1, and the cables and warp-wires are connected by the interwoven weft-wires 4. The interwoven weft-wires 4 have twisted portions 5 encircling the warp-wires and cables at their points of intersection therewith. The wires 4 form the boundary-lines of longitudinally and transversely aligned rows of diamond-shaped figures 6, and the figures 6 in each longitudinal row thereof are bisected by one of the straight warp-wires 3.

What is claimed is—

The design for a wire-fence pattern, herein shown and described.

In testimony that I claim the foregoing as my own I have hereto affixed my signature in the presence of two witnesses.

ALVA L. KITSELMAN.
